UNITED STATES PATENT OFFICE.

THOMAS LUND, OF BEVERLY, MASSACHUSETTS, ASSIGNOR TO UNITED SHOE MACHINERY CORPORATION, OF PATERSON, NEW JERSEY, A CORPORATION OF NEW JERSEY.

DISTRIBUTING APPARATUS.

Application filed July 3, 1919. Serial No. 308,527.

To all whom it may concern:

Be it known that I, THOMAS LUND, a citizen of the United States, residing at Beverly, in the county of Essex and State of Massachusetts, have invented certain Improvements in Distributing Apparatus, of which the following description, in connection with the accompanying drawings, is a specification, like reference characters on the drawings indicating like parts in the several figures.

My invention relates to apparatus for distributing various objects, for example nails for delivery to shoe machinery, as heel-attaching machines.

A feature of the invention concerns means for delivering the distributed objects with like extremities in the same direction, for instance nails with their heads foremost. In the accomplishment of this purpose, the nails pass over a conveyor along grooves, in which are openings provided with a closure. This closure is moved to deliver nails through the opening to a balancing support or bar, which determines the position in which the nails advance. Preferably, the nails are received by depressions in the conveying grooves, and released therefrom to the balancing support by a movable wall, with which said support is shown as traveling.

Another feature of the invention has to do with the manner of operating the closure for the discharge opening, it being movable outward and in the direction in which gravity acts to deliver the nails or other objects. This lessens the resistance to movement of the closure, and, when the nails are held in receiving depressions, nullifies the tendency to roll the nails therefrom in the travel of the closure.

To facilitate the delivery of the nails, a further feature of the invention consists in vibrating the closure of the discharge opening, this action preferably taking place only during the discharging movement of the closure. When the balancing means is carried by the closure, the shake imparted to it also renders more certain the fall of the nails therefrom.

Still another feature of the invention relates to the adjustment of the apparatus for distributing objects of different lengths, this being accomplished by means at opposite extremities of the nail-receiving depressions,

which constitute variable end walls therefor. These maintain the ends in symmetrical relation to the center of the depression, which is of especial advantage when balancing means is located in proximity to said center.

In operating a movable distributing receptacle with a discharge device by which nails or other objects are received one by one for successive delivery, a plurality of nails may so co-operate with the device as to clog therein. To avoid this difficulty, a member, between which and the discharge device there is relative movement, may act to clear from the device the excess of nails. To prevent interference with the entrance of nails to the discharge device, a feature of the invention consists in maintaining the discharge device and clearing member in fixed relation during a portion of the movement of the receptacle. In the embodiment of the invention herein illustrated, the receptacle oscillates in two directions, as upon opposite sides of a central position, and the clearing member therein moves across the discharge device during the oscillation in one direction. I prefer to have this clearing action occur just prior to the opening of the nail-receiving depression.

Varying types of shoes call for the employment of different numbers of nails to secure their heels, which nails may or may not differ in length. It is desirable that the distributing apparatus be so organized as to furnish any of the nail loads which it is to deliver to the heel-attaching or other machine without the necessity of wasting back to the source nails discharged from the distributor, as to its nail-tubes. In such connection, a feature of the invention consists in disposing discharge devices controlling openings in the nail receptacle in groups organized to deliver from the mass in the receptacle the exact number of each of a plurality of diverse loads. In the illustrated organization the nail-receptacle is arranged in compartments, each provided with discharge controlling devices varying in number in different compartments.

Other features will be hereinafter described and claimed, reference being had to the accompanying drawings, in which—

Fig. 1 is a side elevation of one embodiment of the invention;

Fig. 2 is an end elevation looking from the right in Fig. 1, parts being broken away;

Fig. 3 is a longitudinal section on the line 3—3 of Fig. 2;

Fig. 4 is a partial transverse section on the line 4—4 of Fig. 1;

Figs. 5 and 6 are broken perspective views of the grating at the bottom of the nail-receptacle and the shutter co-operating therewith; and

Figs. 7 and 8 are sectional details, illustrating the co-operation between the actuating and vibrating levers for the shutter and their cams.

The frame of the apparatus consists of a horizontal base 10, from which rise opposite vertical arms 12, 12. At the upper extremities of the arms are located bearings 14 for alined horizontal spindles 16, to which, within the arms of the frame, is attached, by set-screws 18, a nail-pot or receptacle 20. This receptacle I have shown as of rectangular form, with its upper side open and with portions 22 overhanging the interior of the receptacle from the top of the side walls to prevent the overflow of the contents when it is tilted. In the bottom of the receptacle are parallel longitudinal grooves 24, acting as nail-ways or conveyors and each containing a discharge device, which will be later described. The bottoms of these grooves preferably are curved transversely, this tending to prevent clogging. To adapt the receptacle for handling a plurality of differing loads of nails for various nailing operations, it is divided into a suitable number of compartments by longitudinal partitions 26. The compartments preferably vary in width and have the conveying grooves differing in number in different compartments. This allows the apparatus to be utilized for delivering, in varying combinations, different numbers of nails, which also may be unlike in length. The number of discharge devices and their corresponding grooves 24 may be so assigned to the compartments that, by placing nails in one or more of these, the exact number of nails will be delivered which is required, as the load for any heel to be operated upon by the machine supplied from the distributor. Ordinarily heels are attached to shoes with either five, seven, nine, eleven, thirteen or fifteen nails. I therefore divide the receptacle 20 into five compartments, having, respectively, four, four, three, two and six conveying grooves and their discharge devices. It will be seen that by the proper selection of these compartments, only such tubes need receive nails as are to deliver them to the loading mechanism of the heeling machine. This, of course, facilitates the preparation of the distributing apparatus for use in a particular nailing operation. At one extremity of each compartment is an opening,

normally covered by a closure furnished by a door 25 hinged at its upper extremity and having at the bottom some convenient form of securing means. These doors may be opened separately, and the receptacle tilted to empty the particular compartment desired, to prepare for the introduction of another size of nail. At a point intermediate the ends of the receptacle, it being in the present instance illustrated as nearer the left-hand end, as viewed in Figs. 1 and 3 of the drawings, there is an open section in the bottom wall, partially closed by a transverse grating 28 supported by ways 30 formed at the edges of the opening. Grooves 32 formed in the upper face of the grating are alined with and continue the receptacle grooves 24, and contain openings 34, the length of which is such as to permit the passage of the longest nail which is to be distributed. The nails in their travel from the grooves 24 are guided and prevented from passing from one groove 32 to another by bars 27, which are set at their ends in the bottom of the receptacle and span the open section. At one edge of each of the openings 34 is an inclined wall 36, shown as lying at an angle of substantially 45 degrees to the upper face of the grating, this furnishing one supporting surface of each of a series of nail-receiving depressions lying at the top of the grating openings. At the opposite side of each opening 34 from the wall 36 is a downwardly inclined wall 38, with which contacts a correspondingly inclined face 40 upon transverse bars 42 of a shutter 44. At the upper edge of each of the shutter bars is a wall 46, this having an inclination substantially equal and opposite to that of the wall 36, and co-operating therewith to complete the nail-receiving depression when the shutter is at its upper position, closing the openings 34. To maintain the shutter normally in this raised position, springs 48 extend between eyes 50 at the corners of the shutter and pins 52 projecting from the opposite sides of the receptacle. Nails caught in the depressions are discharged by moving the shutter from the openings obliquely upon the walls 38 against the tension of the springs 48 by actuating mechanism, which will be hereinafter described. Carried by the shutter, below the faces 40 and extending transversely of and in proximity to the centers of the openings 34, is a balancing support, which may consist of a bar 54, upon which the nails fall and are deflected in the direction of greatest weight, that is, with the heads downward. As they fall they are received by a guide-hopper 56 secured across the bottom of the receptacle 20 below its transverse opening and having a central deflector 58, which so directs the nails at both sides as to prevent their bridging and choking the

passage through the hopper. At its lower extremity the hopper leads into passages 60 in a thin downward extension 62. In the position of the receptacle illustrated in Figs. 5 1 and 3, the passages 60 deliver to nail-tubes 64 (Fig. 2), supported by a head-bar 66 extending between the arms 12 of the frame, these tubes leading to loader mechanism associated, for example, with a heeling 10 chine, neither the loading mechanism nor the associated machine, however, being herein illustrated. To enable the operator to clear the hopper, if by any chance it become obstructed, the side 68 is made removable, being secured in place by a screw 70 pivoted at the opposite side of the hopper, and passing through a slot 72 in the removable wall, which is clamped in position by a nut 74. When this nut is loosened and the screw 20 swung downwardly about its pivot, the nut may pass through an enlarged opening 76 below the slot, so that the wall 68 may be withdrawn entirely from the body of the hopper to give access to the interior.

25 To enable different lengths of nails to be used in any of the compartments of the receptacle, each of these is provided with means for simultaneously adjusting the length of the openings 34 in such compartment. At the opposite ends of the bottom wall of the receptacle are longitudinally extending ways 78, 78, in which are mounted slides 80, 80, carrying at their inner ends, extending up beneath the bottom of the hopper, transverse T-shaped guides 82. Upon these guides are carried bars 84, entering slots 86 lying longitudinally of the bottom of the receptacle. At the inner end of each bar is a reduced finger or projection 88 extending into an opening 34 and continuing the bottom of a corresponding groove 24. All the fingers carried by the bars mounted upon any pair of slides operating within a single compartment may be simultaneously adjusted toward and from one another, so that their ends may be kept symmetrically spaced from the center of the openings 34 and the associated balancing bar, by aligned screws 90, 90 threaded 40 through openings parallel to the bottom of the receptacle formed in lugs 92 depending therefrom. Near the outer end of each screw, adjacent to its actuating head, are pairs of flanges 94, 94, lying at opposite sides 45 of a slot in a lug 96 extending downwardly from the inner end of a slide 80. The screws 90 are preferably joined to turn together, so that the adjustment of the fingers 88 may be made by turning a single screw, 50 by a sleeve 98 fixed to one of the screws and joined to the other by a pin-and-slot connection 100.

55 Journaled in the lower enlarged portions of the frame arms 12 is a horizontal driving shaft 102, upon one end of which

is rotatably mounted a pulley 104, to which power may be applied from any suitable source. The pulley may be connected to the shaft 102 to cause it to be driven, by a single rotation clutch 106 controlled by 50 a lever system 108 from the machine supplied, which does not appear. Secured near one extremity of the shaft 102 is a pinion 110 meshing with a gear 112 fixed upon a shaft 114 journaled in the frame 55 parallel to the shaft 102. Projecting from the outer side of the gear is a crank pin 116 joined by a connecting rod 118 to a pin 120 at one side of the receptacle 20. As the shaft 114 rotates, the connection to 60 the receptacle, starting from the horizontal position appearing in Fig. 1 of the drawings, tilts said receptacle first to the left in the direction indicated by the light arrow, then restores it to the horizontal position, and thereafter tilts it to the right, as indicated by the heavy arrow, finally returning it to the position of Fig. 1. In 65 this movement nails carried in the receptacle pass across the discharge devices in 70 opposite directions, giving two opportunities for their reception by the depressions. Upon the shaft 114, just within the left-hand arm 12 (Fig. 2), is fixed a disk 122, near the periphery of the outer face of 75 which is a cam-depression 124. With the face of the disk, so that it may enter the depression in the rotation of the cam, contacts a projection 126 upon a lever 128 80 fulcrumed at 130 on the frame. To hold 85 the projection 126 against the cam-disk, a spring 132 is interposed between the end of the lever and a plate 134 covering an opening in the frame arm. The upper end of the lever 128 has drawn into co-operation 90 with it by the springs 48 a lug 136 depending from one extremity of the shutter 44. When the projection 126 of the lever is riding upon the face of the cam, the opposite 95 end is so held that the springs 48 may move 100 the surfaces 40 of the shutter over the grating surfaces 38 to close the openings 34, this permitting the reception and temporary retention of the nails in the depressions. When the cam-depression 124 reaches the lever projection in the rotation 110 of the disk, the spring 132 forces the bottom of the lever 128 to the right (Fig. 2), the upper extremity in contact with the projection 136 drawing the shutter down- 115 wardly and to the left (Fig. 4) to free the openings 34 for the delivery of the nails. Since the supporting walls 46 move in part 120 in the direction in which gravity acts and away from the fixed side of the nail-receiving depression, the resistance to shutter movement is minimized, and there is no 125 danger of catching the nails between the relatively movable parts or forcing them out of the depressions into the interior of 130

the receptacle. Fulcrumed at 138 on the frame is a lever 139, having at its lower end a pivoted contact rod 140 operating in an opening in a boss formed on the frame. 5 The outer end of this rod co-operates with a cam-disk 142 rotatable with the pulley 104 and having a plurality of actuating projections. The upper extremity of the lever 139 extends into proximity with the shutter 44, though not in operating contact therewith, as regards the effect of the cam 142, while the shutter closes the openings. When, however, the travel of the upper end 10 of the lever 128 causes the shutter to shift 15 to the left (Fig. 2), the end wall of the latter is carried against the upper extremity of the lever 139, and the projections of the cam 142 cause its vibration with a hammer effect against the shutter, this serving 20 to facilitate the movement of the nails from the depressions, and also being useful in increasing their tendency to overbalance upon the bar 54 for discharge, heads down, into the hopper 56.

25 When a single nail is supported upon the walls 36, 46 of each receiving depression, it may be discharged with certainty by the downward movement of the wall 46. But often the nails are not properly seated in the 30 depressions, and there may be two nails in such engagement that they clog an opening 34 when the shutter 44 operates to release them. To obviate difficulties of this character, a clearing member preferably acts 35 over each opening in the grating. I have shown for this purpose a series of movable claws 144 pivoted upon arms 146 adjustably held by set-screws 148 in openings in a shaft 150, journaled in the opposite walls of the 40 receptacle 20. Each claw is so aligned with a conveying groove that it spans and does not disturb a single nail seated in a receiving depression. But, if there are plural nails so engaged that they rise above the 45 proper level, the claws come into contact with the uppermost and move it clear of the depression and the nail retained therein. Springs 152 preferably connect the pivoted claws and their supporting arms so that 50 the former may come into full contact with the bottom of the receptacle, and then yield as they travel over it. Since the passage of the claws over the depressions during the reception of nails would tend to interfere with 55 this, their movement occurs during a portion only of the oscillations of the receptacle. Thus, in the present instance they exercise their clearing effect upon the oscillation of the receptacle in one direction just 60 before the walls 46 open the depressions to cause the discharge of the contained nails. Secured upon one end of the shaft 150 outside the wall of the receptacle is a pinion 154 meshing with a gear 156 normally free to 65 turn about the spindle 16. Fastened to ro-

tate with this gear is a disk 158 having depressions or teeth about its periphery, with which may co-operate a detent 160 pivoted upon the outer face of the adjacent frame arm and urged toward the disk at its upper end by a weighted lower extremity 162. Fixed to the end of the spindle outside the toothed disk 158 is a cam-disk 164, the edge of which is movable into contact with a pin 166 projecting from the outer side of the 70 detent above its pivotal point. In the horizontal position of the receptacle, the angular relation and contour of the disk 164 are such that the detent may engage the teeth of the disk 158. Then, as the receptacle oscillates to the left (Fig. 1), the edge of the cam disk, acting against the pin 166, forces the detent out of engagement with the teeth, allowing the gear 156 and the pinion 148 to 75 travel with the receptacle without rotation about their axes. It will be evident that, for this purpose, the resistance of the shaft 150 to rotation must exceed the resistance offered by the gear 156 and disk 158 upon the spindle 16. This may be controlled, if 80 desired, by the application of pressure to the shaft 150, as by a spring 168 fixed at one extremity on the receptacle and bearing on the shaft. After its oscillation to the left and during the oscillation to the right, the 85 detent is permitted by the cam to move back into co-operation with the teeth of the disk 158, but while the right-hand end of the receptacle is descending, the inclination of the teeth of the disk is such that they slip 90 freely over the detent. When, however, this end of the receptacle rises for the completion of the oscillation to the right, the engagement between the detent and one of the 95 teeth locks the disk 158 and the gear 156 to 100 the frame. Now the pinion 154 is revolved about it and is rotated about its own axis by the temporarily fixed gear, so that, just before the receptacle reaches its final horizontal or nail-discharging position, the 105 claws 144 make complete revolutions, sweeping over the receiving depressions and clearing them of clogged nails.

110 In using the apparatus, as many compartments as may be necessary are supplied with the desired lengths of nails, and the openings adjusted by the screws 90 to correspond to the particular length within each compartment. Upon the starting of the apparatus, the receptacle performs a double 115 oscillation from its initial horizontal position, causing the nails to sweep twice across the receiving depressions, so that a nail is received by each. As the final oscillation is being completed, the clearing members act 120 to free the depressions of clogged nails, and, just before the stopping point of the receptacle is attained, the projection upon the shutter-actuating lever reaches the depression in its cam, moving downwardly the 125 130

- bottom walls of the depressions, which are simultaneously vibrated by the associated lever, and dropping the nails upon the balancing bar. From this they pass, either to 5 the right or to the left, through the hopper passages to the nail-tubes, and are delivered to the machine to be supplied. If the size of nails in a compartment is to be changed, the proper door 25 is opened and the receptacle tilted to cause their discharge therethrough to a receiver placed below the end of the receptacle. This may be repeated for different compartments, without danger of mixing the nails.
- 15 Having described my invention, what I claim as new and desire to secure by Letters Patent of the United States is:
1. In a distributing apparatus, a movable receptacle provided with conveying grooves 20 in which are openings, a closure movable from and toward the openings, and balancing means upon the opposite side of the closure from the openings.
  2. In a distributing apparatus, a movable receptacle provided with conveying grooves 25 in which are openings, spaced bars movable out of and into co-operation with the openings, and a balancing bar intersecting the spaced bars.
  3. In a distributing apparatus, a movable receptacle provided with conveying grooves 30 in which are openings, a closure movable from and toward the openings, and a balancing bar extending across the grooves beneath the openings.
  4. In a distributing apparatus, a movable receptacle provided with conveying grooves 35 in which are openings, a closure movable from and toward the openings, and a balancing bar fixed to the opposite side of the closure from the openings.
  5. In a distributing apparatus, a conveyor having an opening, a closure for the opening, and means for moving the closure away from 40 the conveyor to free the opening.
  6. In a distributing apparatus, a conveyor having a receiving depression provided with a lower supporting wall, and means for moving the wall outwardly from the depression 45 in the direction of travel of the distributed articles.
  7. In a distributing apparatus, a conveyor having a receiving depression provided with a delivery-opening normally closed by a supporting wall, and means for moving the wall 50 obliquely to the plane of the outer extremity of the delivery-opening.
  8. In a distributing apparatus, a conveyor having a receiving depression provided with 55 a substantially horizontal supporting wall, and a wall inclined downwardly therefrom, and a supporting member movable over the inclined surface outwardly from and inwardly toward the supporting wall.
  - 60 9. In a distributing apparatus, a movable receptacle provided with conveying grooves in which are openings, there being inclined surfaces beneath the openings, spaced bars movable over said surfaces, and means for moving the bars into and out of co-operation with the openings.
  10. In a distributing apparatus, a conveyor having a receiving depression provided with a delivery-opening normally closed by a supporting wall, means for moving the wall outwardly from the plane of the outer extremity of the delivery-opening, and balancing means extending substantially parallel to said plane of the opening and made accessible through the opening upon outward 75 movement of the supporting wall.
  11. In a distributing apparatus, a movable receptacle provided with conveying grooves in which are openings, there being inclined surfaces beneath the openings, spaced bars 80 movable over said surfaces, and a balancing bar intersecting the spaced bars.
  12. In a distributing apparatus, a conveyor having an opening and a co-operating wall furnishing a closure for the opening, means for moving the wall away from the opening to free said opening and in the opposite direction to close it, and means for vibrating the wall.
  13. In a distributing apparatus, a conveyor having an opening and a co-operating wall furnishing a closure for the opening, means for moving the wall to open and close the opening, balancing means associated with the wall, and means for vibrating the wall.
  14. In a distributing apparatus, a conveyor having a receiving depression provided with a supporting wall, means for moving the wall to open and close the depression, means for vibrating the wall, and balancing means movable with the wall.
  15. In a distributing apparatus, a movable receptacle provided with conveying grooves in which are openings, a closure movable from and toward the openings, and a hammer contacting with the closure.
  16. In a distributing apparatus, a movable receptacle provided with conveying grooves in which are openings, a closure for the openings, means for moving the closure, and a hammer into co-operation with which the closure is moved.
  17. In a nail-distributor, an oscillatory receptacle having nail-ways provided with openings extending in a series transversely to the direction of oscillation, a shutter co-operating with the openings, an actuating lever for the shutter, and a vibratory lever against which the shutter is moved by the actuating lever.
  18. In a nail-distributor, an oscillatory receptacle having nail-ways provided with openings extending in a series transversely to the direction of oscillation, a shutter co-operating with the openings, a lever con-

- tacting with the shutter, a cam co-operating with the lever, a lever acting oppositely upon the shutter to that first named, and a cam for vibrating said opposite lever.
- 5 19. In a distributing apparatus, a conveyor having a receiving depression, and means at opposite extremities of the depression arranged to vary its length.
- 10 20. In a distributing apparatus, a conveyor having a receiving depression, and means at opposite extremities of the depression arranged and connected to move simultaneously to vary its length.
- 15 21. In a distributing apparatus, a movable receptacle provided with conveying grooves in which are openings, and members movable in the grooves at opposite ends of the openings.
- 20 22. In a distributing apparatus, a movable receptacle provided with conveying grooves in which are openings, members movable in the grooves at opposite ends of the openings, and connections between the members to permit them to be moved toward and from one another.
- 25 23. In a distributing apparatus, a conveyor having a receiving depression, means at opposite extremities of the depression arranged to vary its length, means for opening and closing the bottom of the depression, and balancing means situated beneath the depression in proximity to its center.
- 30 24. In a distributing apparatus, a movable receptacle provided with conveying grooves in which are openings, members movable in the grooves at opposite ends of the openings, connections between the members to permit them to be moved toward and from one another, and a balancing bar situated beneath the openings approximately midway between the members.
- 35 25. In a nail-distributor, a receptacle arranged to oscillate at opposite sides of a horizontal position and having nail-ways extending in the direction of oscillation and provided with openings at points removed from both extremities of the receptacle, and means for opening and closing receptacles once for a plurality of oscillations.
- 40 26. In a nail-distributor, an oscillatory receptacle having nail-ways provided with openings, a shutter co-operating with the openings, and a balancing bar beneath the shutter and movable with the receptacle.
- 45 27. In a nail-distributor, an oscillatory receptacle having nail-ways provided with openings extending in a series transversely to the direction of oscillation, a shutter co-operating with the openings, and a balancing bar carried by the shutter and extending across the openings.
- 50 28. In a nail-distributor, an oscillatory receptacle having nail-ways provided with openings, a shutter co-operating with the openings, and means for lowering and rais-
- ing the shutter to open and close the openings.
- 55 29. In a nail-distributor, an oscillatory receptacle having nail-ways provided with openings extending in a series transversely to the direction of oscillation, a grating having inclined walls between the openings, and a shutter movable upon the walls to open and close the openings. 70
- 60 30. In a nail-distributor, an oscillatory receptacle having nail-ways provided with openings, bars lying along the nail-ways and having portions extending into the openings, and means arranged to move simultaneously a plurality of the bars. 75
- 65 31. In a nail-distributor, an oscillatory receptacle having nail-ways provided with openings extending in a series transversely to the direction of oscillation, bars lying along the nail-ways and having portions extending into the openings at opposite extremities, and means arranged to move simultaneously the opposite bars. 80
- 70 32. In a nail-distributor, an oscillatory receptacle having nail-ways provided with openings, bars lying along the nail-ways and having portions extending into the openings at opposite extremities, means arranged to move simultaneously the opposite bars, and a balancing bar mounted midway between the movable bars. 85
- 75 33. In a nail-distributor, an oscillatory receptacle having nail-ways provided with openings extending in a series transversely to the direction of oscillation, bars lying along the nail-ways and having portions extending into the openings at opposite extremities, means arranged to move simultaneously the opposite bars, means for opening and closing the openings, and a balancing bar mounted midway between the movable bars. 90
- 80 34. In a nail-distributor, an oscillatory receptacle having nail-ways provided with openings extending in a series transversely to the direction of oscillation, bars lying along the nail-ways and having portions extending into the openings at opposite extremities, means arranged to move simultaneously the opposite bars, means for opening and closing the openings, and a balancing bar mounted midway between the movable bars. 95
- 85 35. In a nail-distributor, an oscillatory receptacle having nail-ways provided with openings extending in a series transversely to the direction of oscillation, bars lying along the nail-ways and having portions extending into the openings, a slide movable beneath the receptacle and connected to a plurality of the bars, and means arranged to move the slide. 100
- 90 36. In a nail-distributor, an oscillatory receptacle having nail-ways provided with openings extending in a series transversely to the direction of oscillation, bars lying along the nail-ways and having portions extending into the openings, slides movable near opposite extremities of the receptacle and connected to aligned bars, and means arranged to move the slides simultaneously. 105
- 95 37. In a distributing apparatus, a movable receptacle having a discharge device, a clearing member co-operating with the device, said member and device being relatively movable, and means arranged to hold the 110
- 100 38. In a distributing apparatus, a movable receptacle having a discharge device, a clearing member co-operating with the device, said member and device being relatively movable, and means arranged to hold the 115
- 105 39. In a distributing apparatus, a movable receptacle having a discharge device, a clearing member co-operating with the device, said member and device being relatively movable, and means arranged to hold the 120
- 110 40. In a distributing apparatus, a movable receptacle having a discharge device, a clearing member co-operating with the device, said member and device being relatively movable, and means arranged to hold the 125
- 115 41. In a distributing apparatus, a movable receptacle having a discharge device, a clearing member co-operating with the device, said member and device being relatively movable, and means arranged to hold the 130

clearing member and device in fixed relation during a portion of the movement of the receptacle.

37. In a distributing apparatus, a movable receptacle having a discharge device, a clearing member mounted upon the receptacle and movable over the device, and means arranged to hold the member against movement on the receptacle during a portion of the movement of said receptacle.

38. In a distributing apparatus, an oscillatory receptacle having a discharge opening, a clearing member movable across the opening, and means arranged to hold the clearing member against movement across the opening during the oscillation of the receptacle in one direction.

39. In a distributing apparatus, a tiltable receptacle having a discharge opening, means for tilting the receptacle a plurality of times, a clearing member movable across the opening, and means arranged to move the clearing member during one only of the plural movements.

40. In a distributing apparatus, a movable receptacle having a receiving depression, means for opening and closing the bottom of the depression, a clearing member co-operating with the depression, said member and depression being relatively movable, and means arranged to produce the relative movement just prior to the opening of the depression.

41. In a nail-distributor, an oscillatory receptacle having a discharge device, a nail-engaging member mounted upon the receptacle and being movable in proximity to the discharge device, actuating mechanism for the engaging member including elements one of which is movable with the receptacle during a portion of its oscillation, and means for holding said element against movement during another portion of the oscillation.

42. In a nail-distributor, an oscillatory receptacle having a discharge device, a nail-engaging member mounted upon the receptacle and being movable in proximity to the discharge device, actuating mechanism for the engaging member including elements one of which is fixed to the engaging member and another of which is movable with the receptacle during a portion of its oscillation, and means for holding the last-named element against movement during another portion of the oscillation.

43. In a nail-distributor, an oscillatory receptacle having a discharge device, a nail-engaging member mounted upon the receptacle and being movable in proximity to the discharge device, actuating mechanism for the engaging member including elements one of which is movable with the receptacle during a portion of its oscillation, means for holding said element against

movement during another portion of the oscillation, and means for controlling said holding means.

44. In a nail-distributor, an oscillatory receptacle having a discharge device, a nail-engaging member mounted upon the receptacle and being movable in proximity to the discharge device, actuating mechanism for the engaging member including elements one of which is movable with the receptacle during a portion of its oscillation, means for holding said element against movement during another portion of the oscillation, and means movable with the receptacle for controlling said holding means.

45. In a nail-distributor, an oscillatory receptacle having a discharge device, a shaft journaled in the receptacle, a nail-engaging member carried by the shaft, a pinion fixed to the shaft, a gear movable upon the receptacle and meshing with the pinion, and means for holding the gear against movement and freeing it at predetermined times.

46. In a nail-distributor, an oscillatory receptacle having a discharge device, a shaft journaled in the receptacle, a nail-engaging member carried by the shaft, a pinion fixed to the shaft, a gear movable upon the receptacle and meshing with the pinion, means fixed in relation to the receptacle for holding the gear against movement, and means for releasing the holding means.

47. In a distributing apparatus, a movable receptacle having a discharge device, a clearing member co-operating with the device, said member and device being relatively movable, and means including elements movable with the receptacle arranged to hold the clearing member and device in fixed relation during a portion of the movement of the receptacle.

48. In a nail-distributor, an oscillatory receptacle having a discharge device, a shaft journaled in the receptacle, a nail-engaging member carried by the shaft, a pinion fixed to the shaft, a gear movable upon the receptacle and meshing with the pinion, a detent for holding the gear against movement, and a cam movable with the receptacle and acting upon the detent.

49. In a nail-distributor, a frame, a receptacle mounted upon the frame and having a discharge device, a spindle fixed to the receptacle and journaled in the frame, a shaft journaled in the receptacle, a nail-engaging member carried by the shaft for co-operation with the discharge device, a pinion fixed to the shaft, a gear and a toothed disk mounted to turn about the spindle, a cam fixed to the spindle, and a detent movable upon the frame for co-operation with the disk and co-operating with the cam.

50. In a nail-distributor, a nail-receptacle arranged to contain nails in a mass and having groups of openings, and discharge de-

vices arranged to deliver through the openings the exact number of each of a plurality of loads of nails differing in number.

51. In a nail-distributor, a nail-receptacle operable to deliver nails in successive loads and having compartments, each provided with discharge devices varying in number in different compartments and controlling the number of nails leaving each compartment for each operation of the receptacle.

52. In an oscillatory nail-distributor, a nail-receptacle having compartments, each provided with discharge devices varying in number in different compartments and over

which the nails travel in the oscillation of 15 the receptacle.

53. In a nail-distributor, a nail-receptacle having compartments, each provided in its wall with conveying grooves with each of which is associated a discharge device, the 20 grooves varying in number in different compartments and being arranged in groups capable of combination to deliver the exact number of each of a plurality of dissimilar loads of nails to be distributed. 25

In testimony whereof I have signed my name to this specification.

THOMAS LUND.

Certificate of Correction.

It is hereby certified that in Letters Patent No. 1,439,013, granted December 19, 1922, upon the application of Thomas Lund, of Beverly, Massachusetts, for an improvement in "Distributing Apparatus," an error appears in the printed specification requiring correction as follows: Page 8, line 11, claim 52, for the words "In an oscillatory nail-distributor a" read *In a nail-distributor, an oscillatory;* and that the said Letters Patent should be read with this correction therein that the same may conform to the record of the case in the Patent Office.

Signed and sealed this 13th day of February, A. D., 1923.

[**SEAL.**]

KARL FENNING,
Acting Commissioner of Patents.
